UNITED STATES PATENT OFFICE.

LUCIEN STEPHEN CRANDALL, OF NEW YORK, N. Y.

DESIGN FOR A DISPLAY-FRAME.

SPECIFICATION forming part of Design No. 30,860, dated May 23, 1899.

Application filed March 22, 1899. Serial No. 710,041. Term of patent 14 years.

To all whom it may concern:

Be it known that I, LUCIEN STEPHEN CRANDALL, a citizen of the United States, residing at New York, county and State of New York, have invented and produced a new and original Design for Display-Frames, of which the following is a full, clear, and exact description, reference being had to the accompanying drawings, in which—

Figure 1 is a front elevation of the frame, and Fig. 2 is a vertical central section thereof.

The leading and characteristic features of my design are the frame A, shown as rectangular in outline, and the bulbs B, circular in outline, disposed upon said frame, as shown. The circular bulbs are disposed upon the frame in groups or series, a group of five bulbs (indicated by 1 and 6) being disposed at each end of the frame, a group of two figures (indicated by 2, 5, 7, and 10) being disposed at the respective corners, a group of three figures (indicated by 3, 4, 8, and 9) disposed two groups along each side, a group (indicated by 11) arranged in two series converging toward the top of the frame, a group (indicated

by 12) arranged in two series converging toward the bottom of the frame, a central group (indicated by 13) substantially elliptical in form and disposed around the center of the frame, including one bulb arranged substantially in the center of the frame, a group of two bulbs (indicated by 14) disposed adjacent the divergent ends of the group 11, a group of two bulbs (indicated by 15) arranged adjacent the ends of the group 12, and a bulb (indicated by 16) disposed on each side of the frame and substantially midway between the central group and the side groups 3 and 4 and 8 and 9, respectively, and a bulb (indicated by 17) disposed at each end of the central ellipse.

I claim—

The design for a display-frame as herein described, and shown in the accompanying drawings.

LUCIEN STEPHEN CRANDALL.
